Patented Feb. 23, 1915.

WITNESSES:

INVENTOR

UNITED STATES PATENT OFFICE.

SAMUEL E. SPERRY, OF WOODHAVEN, NEW YORK, ASSIGNOR TO INTERNATIONAL TYPESETTING MACHINE COMPANY, OF NEW YORK, N. Y., A CORPORATION OF NEW YORK.

LINOTYPE-MACHINE.

1,129,749.

Specification of Letters Patent. Patented Feb. 23, 1915.

Application filed August 16, 1912. Serial No. 715,454.

To all whom it may concern:

Be it known that I, SAMUEL E. SPERRY, a citizen of the United States, residing at Woodhaven, in the county of Queens and 5 State of New York, have invented new and useful Improvements in Linotype-Machines, of which the following is a specification.

The present invention relates to improvements in molds for linotype machines, and 10 its primary object is to provide simple and improved means for casting a hollow slug which possesses advantages over such hollow or skeleton slugs as have been produced heretofore, there being but one piece located 15 between the mold cap and body to regulate the length and thickness of the slug to be cast and to produce hollow spaces which open into the bottom of the slug, the slugs produced according to the present invention 20 enabling single type to be packed against them. Also, the means provided by the present invention for producing such slugs may be properly positioned in the mold with facility, the core being preferably combined 25 with or formed as a part of one or both of the liners which serve to gage the space between the mold body and cap.

To these and other ends, the invention consists in certain improvements, and combinations and arrangements of parts, all as 30 will be hereinafter more fully described, the novel features being pointed out particularly in the claims at the end of the specification.

35 In the accompanying drawing:—Figure 1 is a perspective view of a linotype mold as viewed from the front and showing the same fitted with a liner according to the present invention; Fig. 2 represents a front elevation of the mold, partly in section; Fig. 3 represents a transverse section through the mold, the liner therein, and showing a line of matrices presented to the mold by the matrix elevator or carrier; Fig. 4 represents 40 a horizontal longitudinal section through the mold immediately below the plane of the mold cap; Fig. 5 is a perspective view of the core combined with the liners; Fig. 6 is a perspective view of a slug of the kind produced by a mold embodying the present invention.

Similar parts are designated by the same reference characters in the several views.

45 The present invention is applicable generally to machines for casting lines of type

in the form of slugs and is particularly adapted to be used in connection with the well known Mergenthaler linotype machines, it being shown in the present instance as applied to a mold adapted for use in connection with such machines, the mold comprising a mold body 1 which is adapted to be secured as usual to the mold wheel or disk, a mold cap 2, and screws 3 which serve to secure the cap in proper position on the 60 mold body. In the present invention, a single liner is employed to gage the distance between the mold body and cap, such liner embodying the end sections 4 and 5, and the liner is reduced in thickness and width for 65 a part of its length by cutting away a portion of its upper and lower surfaces and of its front edge to provide the reduced core section 6, thereby forming a U-shaped cavity when the liner is in place in the mold, said 70 cavity extending in an unbroken line along the faces of the mold body and cap, the center of said cavity midway between the body and cap being occupied by the reduced part 6 of the liner. In the present instance, such 75 sections 4 and 5 of the liner are adapted to be interposed between the respective ends of the mold cap and body, and the different parts of the mold are clamped firmly together by the screws 3. In order to accurately position the different parts of the 80 mold, the screws 3 are preferably surrounded by bushings 7 which coöperate with the mold cap and the liners. A dowel 8 is also 85 preferably used to assist the screws and bushings in positioning the different parts of the mold correctly.

According to the present invention, the core section 6 is provided which is adapted to be so positioned in the mold cavity that 90 the metal when introduced into the mold will cover the top and bottom and front edge of the core whereby the core cavity thus produced will be contained wholly within the 95 slug, and the top and bottom faces of the 100 slug will be intact or free from recesses or other depressions, the core chamber being open to the exterior of the slug only at the back thereof. In order to facilitate separation of the cast slug from the core, the latter 105 is preferably beveled or tapered in transverse section, as shown, and in order to stiffen or reinforce the faces of the slug, a suitable number of notches 9 are formed in the core and extend rearwardly from the 110

front edge thereof, these notches being also preferably tapered as shown to facilitate separation of the cast slug from the core. The slug 10 which is produced by the aid of 5 a core of this construction has the top and bottom flat faces 11 and 12 thereof smooth and uninterrupted by recesses or other depressions, thereby enabling lines of single type to be packed at either or both sides of 10 the slug, and the core cavity 13 is divided in a direction longitudinally of the slug by transverse webs 14 which connect those portions of the slug at opposite sides of the core chamber, the slug possessing substantially 15 the strength of the ordinary solid slug, although it is lighter in weight and requires the use of less metal. In the preferred embodiments of the invention, the core is combined with the liners, as this arrangement 20 facilitates the handling of the core and insures proper positioning of the core within the mold cavity. In the present instance, the core is attached to or formed as a part of the end sections 4 and 5 of the liner, and 25 when the liner is placed in the mold, correct positioning of the core in the mold cavity is insured. To facilitate application and removal of the liner and core, the liner section 4 may be formed with open slots or recesses 15 and 16 extending inwardly from 30 the end and adjacent side thereof to receive the dowel 8 and the corresponding bushing 7, and the liner section 5 may be provided with a slot or recess 17 extending inwardly 35 from one side thereof to receive the bushing 7 at the corresponding end of the mold, it being only necessary to swing the liner about the dowel 8 as an axis in order to remove and insert these parts, and the screws 3 when 40 tightened serve to secure the parts in proper relation. The elevator or carrier 18 may serve in the usual way to position a line of matrices 19 before the mold, preparatory to the casting operation, this line of matrices 45 closing the front of the mold cavity, as usual, and the metal may be introduced at the opposite side of the mold by the usual metal pot.

The casting of hollow slugs is desirable 50 when slugs of comparatively large size are used, not only for the purpose of diminishing the weight of metal in the slugs, but also to allow the slugs to chill more quickly. Hollow or skeleton slugs have heretofore 55 been produced in different ways, although the principal method has been to employ a

core which was placed adjacent to one side of the mold, and hence, the slug cast with that arrangement had recesses or depressions in the top or bottom side thereof. A slug of 60 that form was objectionable for several reasons, and notably because it precluded the packing of a line of single type against the recessed side thereof, for the reason that the feet of the type would enter the recess in the 65 slug. Such objections as were found to exist with the previous arrangement have been obviated by the present invention which enables a slug of improved form to be produced, and the handling and positioning of 70 the core is greatly facilitated.

I claim as my invention:—

1. In a mold for linotype machines, a core, and liners for positioning the core in the mold cavity and in spaced relation to the cap 75 and body thereof.

2. In a mold for linotype machines embodying members forming the sides thereof, and a core having liners connected thereto for supporting it in the mold cavity in 80 spaced relation to said side-forming members.

3. The combination of a mold for linotype machines, a core, and liners for positioning the core centrally between the sides of the 85 mold cavity.

4. In a mold for linotype machines having a mold body and cap, liners for spacing the distance between the body and cap and having a core connected thereto and filling a 90 portion of the mold cavity to form a cored slug.

5. The combination of a mold having a cavity for casting a line of type, and a core having liners coöperative with the ends 95 thereof for positioning the core intermediate the top and bottom walls of the mold cavity.

6. The combination of a mold having a cavity for casting a line of type, and a core having liners for positioning it in the mold 100 cavity and extending forwardly from the rear edge thereof, the forward edge of the core having web-forming notches extending rearwardly from the forward edge thereof.

In testimony whereof I have hereunto set 105 my hand in presence of two subscribing witnesses.

SAMUEL E. SPERRY.
